UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A HANDLE FOR SPOONS, &c.

SPECIFICATION forming part of Design No. 23,209, dated April 24, 1894.

Application filed March 1, 1894. Serial No. 502,000. Term of patent 3½ years.

To all whom it may concern:

Be it known that I, CHARLES OSBORNE, a citizen of the United States, residing in the city, county, and State of New York, have invented and produced a new and original Design for a Handle for Spoons, &c., of which the following is a specification, reference being had to the accompanying drawings, forming a part thereof.

Figure 1 is a plan view of the obverse side of the handle. Fig. 2 is a similar view of the reverse side; and Fig. 3 is a broken detail view showing the shape of the handle in cross section at certain points.

The leading features of my design are the plain tapering body portion of the handle, the foliated figure at the top of the handle having in the center the representation of a cluster of grapes, and the scroll-like figures extending downward from the base of the handle and provided with flowing tendrils. The handle tapers from the top to a point near the center at which point it is nearly circular in cross section, see Fig. 3, and at the top it has in-turned leaf-like figures, from the central portion of which hangs a figure simulating a cluster of grapes. The design, at this portion of the handle, is similar on the obverse and reverse sides, except that on the obverse side the figures are in a little higher relief. Just below the smaller part of the plain portion of the handle is an enlargement nearly rectangular in cross section, see Fig. 3, the lower portions of which terminate in foliated figures and the side edges of the handle are in relief, while between these raised parts are scroll-like figures, those on the reverse side being short and those on the obverse side extending downward below the base of the handle and being provided with numerous flowing tendrils and with a figure simulating a flower.

I claim—

The design for a handle for spoons, &c., herein shown and described.

CHARLES OSBORNE.
